COMBINATION REGULATED MUTE

Filed Feb. 4, 1926

Fig. 1

Fig. 2

Inventor:
Frederick A. Berg
By J. Daniel Stuwe
his Attorney

UNITED STATES PATENT OFFICE.

FREDERICK A. BERG, OF CHICAGO, ILLINOIS.

COMBINATION REGULATED MUTE.

Application filed February 4, 1926. Serial No. 85,906.

My invention pertains to combination regulated mute, and the main object of the invention is to provide a mute comprising a shell or body of glass or other vitreous material to give a clear sonorous tone; and another object is to construct and shape said body for containing liquid and to provide gage means thereon for gaging the liquid, so as to properly modify the tone effect of the mute and also to adapt the mute to suit various sized instruments; a further object is to provide said mute with a port at the outlet end and with plunger means therein to be used alone or to co-operate with the liquid in the mute to modify the tone effect thereof; and another object is to provide curved spring means for holding the mute in position in wind instruments of various sizes. Other objects and advantages are attained with my invention, as will become apparent from the following description taken in connection with the accompanying drawing, in which,

Fig. 1 is a sectional view showing my invention in the form of a mute for a cornet or similar horn instrument; and

Fig. 2 is a sectional view showing my invention in the form of a mute particularly adapted for a saxophone.

The particular form of my invention illustrated in Fig. 1 of the drawing comprises a tubular and substantially conical shell or body member 5 having an air or sound receiving opening 6 at the inner or smaller end, while its opposite or larger end is substantially closed, preferably by an outwardly curved or bulb-like portion 7 which terminates in a tubular sleeve or neck 8 providing a suitable outlet opening or port for the direct outlet of part of the sound waves, if desired. A plunger or member 9 is slidably mounted in this sleeve 8 and is adapted to entirely close the outlet port, and said plunger is movable into the body to modify the tone effect of the mute and is gaged or marked with numbers so that it may be adjusted or set in the proper position in said sleeve to provide the desired pitch or tone effect. This plunger may be made of cork or any other suitable material.

The body of the mute is made of vitreous material, preferably glass, which it has been found produces a clear and sonorous tone and at the same time provides the desired modified and subdued tone.

The body is constructed to provide a reser-

voir for containing liquid 10, to modify and subdue the tone effect. This liquid may be water, alcohol, oil, or a similar substance. In order to observe the volume of liquid in the body of the mute said body or a part thereof is made of glass or transparent bakelite, celluloid or the like, and along this transparent reservoir or part a gage or graduated means 11 is provided for indicating and determining the amount of liquid to be used. By increasing the amount of liquid 10, and likewise by moving the plunger 9 further into the body 5, the interior space and capacity of the body is decreased and is less subduing and modifying in its tone effect, and therefore more volume of sound emanates directly from the wind instrument with which this mute is used. This regulated mute is thus at once adapted for use with either a large or a small wind instrument, and by regulating the mute, the associated instrument may thus be regulated to synchronize it with the other instruments whether a larger or smaller number of instruments are playing at the same time.

The mute is particularly shaped to suit the inner contour of the instrument with which it is used, and the means for holding this mute in position in the bell 12 of the instrument comprises curved resilient members, which are preferably made each from a curved strip of spring metal 13 with a strip of compressible and frictional material 14, such as rubber, cork or raw-hide, fastened on the outer side thereof. Each of these members is mounted in a pair of holes or openings 15 provided in the side of the body 5, to be frictionally held in the openings, and to be slidable therein. These resilient slideable members thus adapt the mute to be properly supported and retained in instruments of various sizes.

The form of invention shown in Fig. 2 is more particularly constructed and arranged for use with a saxophone, and this form also comprises a tubular or somewhat conical shaped shell or body member 25 having an air or sound receiving opening 26 at its smaller end formed by an inwardly extending or inverted conical part or throat 26', while its opposite or outer end is substantially closed by an inwardly curved or concave portion 27 which terminates in a tubular sleeve or neck 28 providing a suitable outlet port for the passage of part of the sound waves.

A plunger or member 29 is slidably mount-

ed in this sleeve 28, for entirely closing the outlet port, and is movable into the body to modify the tone effect. The plunger is also gaged or numbered so that it may be adjusted in the proper position in the sleeve in order to produce the desired pitch or tone effect with the mute, and this plunger is made of cork or other suitable material.

The body in this form of invention, like 10 in the preceding form, is made of vitreous material, preferably glass, to provide a clear and sonorous tone effect, and also a modified or subdued one.

The body of the mute is constructed and 15 arranged for containing liquid 30, and this is particularly done by extending the neck 26' inwardly as shown. In order to observe the volume of liquid used, the body is made of glass or other suitable transparent material, 20 as in the preceding form, and is provided with a gage or graduated means 31 at the smaller end, or over the reservoir formed by the inverted neck 26'. The increase and decrease 25 of water used in this form, and the adjusting of the member 29, modifies the tone effect of this mute, in the manner described above.

This mute is shaped to suit the inner contour of the bell 32 of a saxophone, and is provided with curved resilient members, 30 which are preferably made of curved strips of spring metal 33 on which are fastened strips of compressible and frictional material 34, for resiliently and movably retaining these members in the opening 35 provided 35 in the body 25 of the mute. These members and their manner of mounting in the body 25 adapts the mute to be mounted in saxophones of various sizes.

What I claim as my invention and desire 40 to secure by Letters Patent is:

1. A mute comprising a body of vitreous material constructed to fit the bell of a wind instrument and having an opening at each end, adapted to transmit air through the 45 body, and means for closing the outer opening and adjustable therein.

2. A mute comprising a body of transparent vitreous material concaved longitudinally on the exterior and rounded at the larger end to 50 fit the bell of a wind instrument and to contain liquid visible through said material.

3. A mute comprising a body of vitreous material having a sound receiving opening at one end and a neck extending outwardly from 55 an outlet opening at the opposite end.

4. A mute comprising a body of transparent material having a sound receiving opening at one end and a sleeve surrounding an outlet opening at the opposite end for the exit of 60 sound, and means readily removable from and slidably in said sleeve and into said body for closing the outlet openings and also to modify the tone effect.

5. A mute, comprising a body of vitreous 65 material, having a sound receiving opening

at one end and a sleeve surrounding an outlet opening at the opposite end, and means for closing the outlet opening and to be movable into the body of the mute to modify the tone effect.

6. A mute, comprising a body, having a sound receiving opening at one end and having the walls of the other end contracted and provided with a sleeve forming a vent port, and means slidably mounted in said sleeve 75 for closing the same and also to be moved into the body to modify the tone effect of the mute.

7. A mute, comprising a substantially conical body open at the smaller end, the larger end being curved inwardly and closed and provided with a sleeve forming an outlet port, and calibrated plunger means slidably mounted in said flange and movable into the mute for enlarging or diminishing the volume of the mute.

8. A mute, comprising a transparent, liquid-containing body, calibrations upon the body to indicate the volume of liquid contained therein, the volume of the liquid adapted to vary the sound modifying effect 90 of the mute.

9. A mute, comprising a liquid containing transparent body, adapted to fit in the bell of a wind instrument, and calibrations on the said body for determining the amount of 95 liquid contained therein.

10. A mute comprising a conical transparent body constructed to contain liquid and having an air entrance at the smaller end, the larger end being curved and having a vent port, means for closing said port, and gage means on said body for gaging the volume of liquid used in said mute to provide the desired pitch.

11. A mute comprising a tubular body having 105 holes in its side wall, and curved spring members movably mounted in said holes and yieldably and frictionally engaging the wall of the wind instrument.

12. A mute comprising a tubular body having holes in its side wall, and curved spring members movably mounted in said holes and having frictional cushioning material thereon for engaging the wall of the instrument.

13. A mute comprising a tubular body having 115 pairs of holes in its side wall and a curved spring member arranged to slidably and frictionally move in each pair of holes for yieldably retaining the mute in a wind instrument.

14. A mute comprising a tubular body having pairs of holes in its side wall, and a curved spring member with yieldable frictional material fastened along its outer side and being frictionally movable in each pair of holes.

15. A mute comprising a vitreous conical body open at the smaller end and having means for closing the larger end, said body having pairs of openings in its side wall, a strip of spring metal with frictional ma- 125 130

terial mounted in each pair of openings and movable therein for mounting the mute in a wind instrument.

16. A combination regulated mute comprising a body of transparent material constructed to contain liquid and having gage means on said transparent material to gage the amount of liquid, one end of said mute being open to receive sound and the other end having a vent port with a member slidably mounted therein to close said port and being movable into said body to co-operate with the liquid for modifying the tone effect of the mute.

17. A mute comprising a conical body of transparent vitreous material having the small end open, the larger end being formed bulb-like and having a flanged opening therein, gage means along said larger end to indicate the amount of liquid used in said body, and means for closing said flanged opening and being movable into the body to co-operate with the amount of liquid used in modifying the tone effect.

18. A mute comprising a conical body of transparent having the smaller end open, the larger end being bulb-shaped and terminating in a flanged opening forming an outlet port, gage means provided along said larger

end to indicate the amount of liquid used in said body, gaged means for closing said flanged opening and being movable into the body to co-operate with the liquid in modifying the tone effect, and curved spring means mounted in openings in said body for mounting said mute in wind instruments of various sizes.

19. A mute comprising a conical shaped body of transparent vitreous material having an inwardly extending tubular portion at the smaller end and being constructed to contain liquid at said smaller end, and gage means provided along said smaller end to indicate the amount of liquid used in said body.

20. A mute comprising a conical shaped transparent body having an inverted conical portion at the smaller end constructed to contain liquid at said end, gage means on said body along said smaller end to indicate the amount of liquid used, a vent port at the larger end of said mute, and means for closing said larger end and being movable into the body to modify the tone effect.

In testimony whereof I have signed my name to this specification.

FREDERICK A. BERG.
